UNITED STATES PATENT OFFICE.

MARK THOMAS DENNE, OF RUSHDEN, ENGLAND.

HEEL-COMPRESSING MACHINE.

1,176,743.

Specification of Letters Patent. Patented Mar. 28, 1916.

Application filed September 11, 1912. Serial No. 719,701.

To all whom it may concern:

Be it known that I, MARK THOMAS DENNE, a subject of the King of Great Britain and Ireland, residing at Rushden, 5 Northamptonshire, England, have invented new and useful Improvements in or Relating to Heel-Compressing Machines, of which the following is a specification.

This invention has reference to improvements in and relating to heel compressing machines of the type in which a blank-supporting table is made to move toward a stationary platen or cross-head to compress the heel blank and thereafter is made to 10 recede to enable the compressed heel to be removed and another blank to be positioned thereon, the movements of the table being usually effected by means of toggle levers.

In accordance with my invention the table 20 on which the heel blank is placed is mounted upon a vertically reciprocating cross-head and directly under the fixed die with which the said table is to coöperate, in such a manner that, while participating in the up-and-down movements of the said cross-head, it can also rock on same, means being provided to cause the said table to swing outward automatically toward the position where the operator is stationed to feed the 25 machine so that the table will be for a brief time held at an angle to the horizontal so that he may have a full and clear view thereof while placing the heel blank thereon. In order to enable the operator to position the 30 blank correctly, the table has removably attached to it those parts of the mold whereby the shaping of the heel seat and the breast 35 are effected.

I have illustrated an embodiment of my 40 invention in the accompanying drawing, in which:—

Figure 1 is a front elevation of my improved heel compressing machine. Fig. 2 45 a rear elevation of the upper portion of said machine, and Fig. 3 a side elevation of the machine with some parts broken away.

Referring to the drawing, 1 represents the base or frame of the machine provided with vertical pillars 2 which fixedly carry 50 at their upper ends a head 3. On the pillars I slidably mount a cross-head 4 the central portion of which comprises a rod or spindle 5. The cross-head is supported and its movement controlled by toggle levers 6, 7 55 in a manner to be hereinafter described.

One end of a link 8 pivotally engages the

toggle levers at their point of junction while the other end of said link is connected to a crank shaft 9 suitably geared to a driving clutch 10 controlled by a treadle or the like 11.

Mounted on the cross-head are two pairs of links 12 adjustable to a slight extent on eccentric pins 13. The links are connected at their inner ends to and control the movements of blocks 14 slidably mounted in guides 15 on the head and said blocks in turn support and engage the two sides 16 which together with a top plate 17 (fixedly attached to the head) form the blank mold. 70

A die support 18 removably carries the breast part 19 and seat part 20 of the blank mold and is formed or provided with a saddle portion 21 rotatably mounted on the rod 5 in a manner to be hereinafter described. 75

The upper end of the toggle lever 6 pivotally engages a saddle or bridge piece 22 which forms the lower portion of a split bearing surrounding and supporting the rod 5 while between the upper portion of said bearing—which consists of caps 23 held in engagement with the lower portion by bolts 24 or the like—and the rod the before mentioned saddle portion 21 of the die support is mounted so that it may turn about the rod 80 85 from the blank receiving position (shown in dot-and-dash lines in Fig. 3) to the blank compressing position.

The die support 18 is formed or provided with arms 25 or the like the free ends of 90 which are preferably provided with rolls 26 or the equivalent engaging in grooves 27 or slots in a bracket 28 or the like formed or provided on a vertically movable rod 29. The said rod is slidably carried at about its 95 upper end in a bracket 30 while its lower end is slidably guided in a sleeve 31 or the equivalent. The upper end of the rod is provided with a lug 32 or the like carrying adjusting screws 33 which on the depression of the rod contact with the upper face of the bracket thereby stopping the depression of the rod. To the lower end of the rod one end of a tension spring 34 is adjustably attached the other end of said spring being fastened to the sleeve 31 or other suitable part of the machine. 100 105

I form or provide the cross beam with a lug or bracket 35 in which is mounted a carrier 36 to slidably retain an ejector bar or finger 37. One end of said bar engages a lever 38 pivotally mounted on a spindle 110

39 provided on the cross beam, said lever being normally held in contact with a stop 40 by a spring 41 or the equivalent. The lower end of the lever has attached to it a 5 lug 42 or the like which as said lever descends—with the cross beam—engages a pivotally mounted trip or catch 43—mounted on one of the pillars or other suitable part 10 of the machine—which through the instrumentality of the lever forces the ejector forward causing it to strike the already compressed blank from its seat.

The operation of the machine is as follows:—Assuming the die support to be in its 15 blank receiving position (shown in dot-and-dash lines in Fig. 3) and a heel to be placed with its seat downward on the mold seat. On starting the machine the toggle levers 6, 7 commence to open forcing the cross beam upward and as the rod 29 is held in its lowermost position by the spring 34 the die support 18 turns about said rod the rolls 26 sliding in a horizontal direction in the slots of the bracket 28. The die support 20 continues to rotate until the edge of its saddle 21 engages the upper face of the bridge piece 22 thereby arresting its turning movement. The toggles then force the cross beam and rod upward overcoming the force 25 of the spring thereby moving the die support upward in a vertical direction and as the blank enters the mold—which entry takes place before the die support has completed its turning movement—its sides 16 30 which have already commenced to approach each other—by virtue of the movement of the links 12 into a more horizontal position—continue to close in. Should the blank become slightly displaced it is able to creep 35 on the side molds into its correct position before the final pressure is applied. A clip 40 or plate 44 is mounted on the head of the machine in a position to insure that the die holder cannot be forced out of position 45 during the compression of the heel blank. On the completion of the compression stroke the toggles commence to collapse drawing the cross beam die support and rod downward, the rod continues to descend until the 50 screws 33 contact with the bracket 30 after which on the continued descent of the cross beam and toggles the rolls are only capable of movement in an inward direction thus causing the die support to rotate about the 55 rod and its blank carrying end to take up a position in which it can be conveniently loaded. Just before however the die support reaches its outermost position the lug 42 engages the trip 43 thus causing the ejector 60 arm 37 to strike or push the already com-

pressed heel blank therefrom after which another heel blank may be placed on the mold seat.

In addition to others my improved machine possesses, the advantage that as the 65 mold is placed in an inverted position ejector mechanism to remove the heel therefrom is not required.

What I claim as my invention and desire to secure by Letters Patent is:—

1. In a heel-compressing machine, the combination with a fixed cross-head, of a tread die mounted on the lower face thereof, a vertically-reciprocating cross head, a table to receive the blank to be compressed 75 mounted upon said vertically-reciprocating cross-head for rocking movement about a pivot situated vertically beneath the tread die, a heel seat die and a heel breast die mounted on said table, means for actuating 80 the vertically-reciprocating cross head, means for maintaining the table in a horizontal position when the cross head is near the upper end of its stroke, means for causing said table to rock on its bearing when 85 said cross head is moving through the lower portion of its stroke, and means for automatically removing the compressed heel from the table.

2. An organized machine of the type 90 specified for compressing heel-blanks, comprising in combination a fixed cross-head, a tread die mounted on the lower face of the 95 said cross-head, a vertically-reciprocating cross-head, a table to receive the blank to be compressed mounted upon the reciprocating cross-head directly below the said tread die, said table having a bearing on which it is arranged to be rocked, a heel-seat die and a heel-breast die mounted on the said table, lateral 100 compressing members or dies for shaping the sides of the blank mounted on the fixed cross-head, means for actuating the vertically-reciprocating cross-head, means for maintaining the table in a horizontal position when the said cross-head is near the 105 upper end of its stroke, means for causing the said table to rock on its bearing when the said cross-head is moving through the lower portion of its stroke, and means for 110 automatically removing the compressed heel from the table, substantially as shown and described.

In testimony whereof I have signed my name to this specification in the presence of 115 two subscribing witnesses.

MARK THOMAS DENNE.
